(74) Attorney, Agent, or Firm — Kilpatrick Townsend & Stockton LLP

(57) **CLAIM**

The ornamental design for a lighting fixture, as shown and described.

DESCRIPTION

FIG. 1 is an isometric view of a lighting fixture. FIG. 2 is another isometric view of the lighting fixture of FIG. 1. FIG. 3 is a front view of the lighting fixture of FIG. 1. FIG. 4 is a right side view of the lighting fixture of FIG. 1. FIG. 5 is a rear view of the lighting fixture of FIG. 1. FIG. 6 is a left side view of the lighting fixture of FIG. 1. FIG. 7 is a top view of the lighting fixture of FIG. 1; and, FIG. 8 is a bottom view of the lighting fixture of FIG. 1. The dashed broken lines in the drawings denote structure that is not part of the claimed design. The long dash-short dash-long dash lines in the drawings denote unclaimed boundaries of the design.

1 Claim, 6 Drawing Sheets
